N. E. GULLERUD

CLOTHES MANGLE

Filed May 16, 1925

FIG. 1.

FIG. 2.

UNITED STATES PATENT OFFICE.

NILS E. GULLERUD, OF MADDOCK, NORTH DAKOTA.

CLOTHES MANGLE.

Application filed May 16, 1925. Serial No. 30,856.

To all whom it may concern:

Be it known that I, NILS E. GULLERUD, a citizen of the United States, residing at Maddock, in the county of Benson and State of North Dakota, have invented certain new and useful Improvements in Clothes Mangles, of which the following is a specification.

This invention relates to clothes mangles. 10 An object of the invention is the production of a clothes mangle which will effectively iron clothes without damage to the buttons or other fastening means attached thereto.

Another object of this invention is the production of a clothes mangle which may be folded up so as to occupy but small space when not in use. A mangle which may be easily and quickly set up or taken down and 20 will efficiently perform its intended functions.

A further object of this invention is the production of a clothes mangle which will be highly efficient in operation, yet of 25 marked simplicity as a whole and in respect to each of its component parts so that its manufacture is economically facilitated both as regard to parts and their assembly.

With these and other objects in view 30 which may be incident to my improvements, the invention consists in the parts and combinations to be hereinafter set forth and claimed, with the understanding that the several necessary elements comprising my 35 invention, may be varied in construction, proportions and arrangement, without departing from the spirit and scope of the appended claims.

In order to make my invention more 40 clearly understood I have shown in the accompanying drawings means for carrying the same into practical effect, without limiting the improvements in their useful application to the particular constructions, 45 which for the purpose of explanation have been made the subject of illustration.

In the drawings forming a part of this specification:

Figure 1 is a front elevation illustrating 50 the complete assembly, a part of which is in section, and

Figure 2 is an end elevation taken on line 2—2 Fig. 1; the top in dotted lines in an open position.

55 Referring by numerals to the drawings 1

represents a bottom section mounted upon the extreme ends of which are parallel vertical side sections comprising lower portions 2 and upper portions 3 hinged together as shown at 4 and provided with locking means 5. The abutting ends of the upper and lower portions 3 and 4 are slotted as shown at 6, the object of which will hereinafter appear. The side sections are connected at their upper ends by a top section 7, secured in a permanent manner.

The bottom section is provided with corresponding right angular arms 8 and 9. Mounted in the arms 9 are thumb screws 10 adapted to clamp between themselves and the arms 8 the edges of a table. The bottom section is further provided with a detachable shelf or table 11 supported by corresponding rods 12 having upon their free end hooks 13 which engage eye screws 14 in the upper edge of the bottom section.

Formed in the upper portions 13 of the side sections are guideways 14. Mounted in the guideways 14 is a U-shaped frame or yoke 15. The yoke or frame 15 is pivotally attached to a screw 16 mounted in the center of the top section 7. The screw 16 is provided with a handle 17 by means of which the screw is revolved to cause the yoke 15 to travel up or down in the guideway 14. 55 Journalled in the yoke 15 is a roller 18, the object of which will hereinafter appear.

Journalled in the lower portions of the side section 2 is a roller 19 and intermediate the rollers 18 and 19, journalled in the slots 90 14 is a roller 20 around which is wound several layers of cloth or fabric 21, the object of which will hereinafter appear. The roller 20 is mounted upon a shaft 22 one end of which projects through one of the slots 6 and is provided upon its projected end with a shoulder 23 adapted to receive a crank 24 having a handle 25 by means of which the roller 20 is revolved. It will be readily seen that by disengaging 95 the locking means 5 the upper portion of the frame may be folded back upon its hinges 4 and the roller 20 removed, for the purpose of replacing the cloth 21. Also by disengaging the locking means the frame 105 may be folded back upon itself so as to be packed away in a compact manner.

Since the fabric upon the roller 20 bears upon roller 19 at a line of tangency and is held in close contact therewith by the roller 110

18 also at a line of tangency and forced down upon the roller 20 by means of the adjustable yoke 15 great pressure may be brought to bear between the rollers. When 5 the machine is thus assembled and in position for operation, any clothes fed thereto will be thoroughly ironed without injury to the buttons or other fastening means sewed upon the cloth, by reason of the yielding 10 or cushion effect of the fabric on the roller. The rollers can be adjustable to permit of the ironing of two or more layers of cloth at one and the same time, the number of pieces fed to the machine at one time can be 15 varied according to the nicety or perfection of the work to be performed, also according to amount of force exerted in the operation of the machine.

While I have shown and described the 20 preferred embodiment of my invention, I wish it to be understood that I do not confine myself to the precise details of construction herein set forth, by way of illustration, as it is apparent that many changes and 25 variations may be made therein, by those skilled in the art, without departing from the spirit of the invention, or exceeding the scope of the appended claims.

Having thus described the various features of my invention, what I claim as new 30 and desire to secure by Letters Patent is:

1. In a mangle, a two part frame, a roller 35 journaled in the lower part an adjustable member within the upper part, a roller journaled within the adjustable member, an intermediate roller means for rotating the intermediate roller and a detachable shelf supported by the lower part.

2. In a mangle, a two part frame, a roller 40 journaled in the lower part an adjustable member mounted in the upper part, a roller journaled in the adjustable member, slots in the abutting ends of the two parts, an intermediate roller mounted in the slots, means for removing the intermediate roller and 45 means for rotating the intermediate roller.

3. In a mangle, a two part frame, a roller 50 journaled in the lower part, a sliding member mounted in the upper part, means for adjusting the sliding member, a roller journaled in the sliding member, an intermediate roller, means for removing the intermediate

roller, and means for rotating the intermediate roller.

4. In a mangle, a frame comprising parallel side sections, top and bottom sections, means carried by the bottom section for supporting the frame, the side sections being composed of two parts hinged together and provided with locking means, a sliding member mounted in the frame between the upper parts of the side sections, a roller journaled in the sliding member, means for adjusting the sliding member, a roller journaled between the lower parts of the side sections, an intermediate roller, and means for rotating the intermediate roller. 55

5. In a mangle, a frame comprising parallel side sections each formed in an upper and a lower half hinged together and provided with locking means, corresponding slots in the abutting ends of the two halves, top and bottom sections connecting the side sections, means for supporting the frame, a sliding member mounted in the upper halves of the side sections, means for adjusting the sliding member, a roller journaled in the sliding member, a roller journaled in the lower halves of the side sections, 75 an intermediate roller journaled in the slots in the side sections, and means for rotating the intermediate roller. 70

6. In a mangle, a frame comprising parallel side sections, top and bottom sections connecting the side sections, means carried by the bottom section for supporting the frame, a shelf detachably supported on the bottom section, the side sections formed in upper and lower portions hinged together and provided with locking means, the abutting ends of the upper and lower portions of the side sections having corresponding slots, a sliding frame mounted in the upper portions of the side sections, means for adjusting the sliding frame, a roller journaled in the sliding frame, a roller journaled in the lower portions of the side sections, an intermediate roller journaled in the slots in the side sections, and means for rotating the intermediate roller. 85 90 95

In testimony whereof I affix my signature.

NILS E. GULLERUD.
